OIL GAS GENERATING PROCESS

Walter B. Harris, Bayside, Long Island City,
N. Y.

Application July 22, 1935, Serial No. 32,524

2 Claims. (Cl. 48—214)

This invention relates to an oil gas generating process comprising the steps of first raising steam to a temperature at which substantially all of it will react when brought into the presence of hydrocarbon, then bringing said steam into direct contact with hydrocarbon oil and then causing reaction under high heat influence, the said steps taking place continuously.

This application is a continuation in part of my application for patent for Oil gas generator, Serial No. 742,322, filed August 31, 1934.

I have disclosed herewith a means for raising by vacuum a regulated quantity of oil from a fixed level below an injector nozzle and causing the kinetic energy of steam passing through the nozzle at said reaction temperature to inject the oil into a gasifying chamber within an oil gas generator. This oil injecting means eliminates the use of pressure oil pumps having moving parts or of gravity oil feed. I have found in practice that this vacuum method of feeding the oil provides a safety feature in the operation of the gas plant in that no oil can be raised from the lower level and admitted into the gas generating chamber unless the superheated steam is present and under a predetermined pressure. I use this method of feeding the oil into the oil gas generator herewith disclosed and utilize the kinetic energy of steam superheated to said reaction temperature to inject the oil.

I have disclosed herewith an oil gas generator having a regulated water level boiler with a steam chamber and having superheating tubes leading to the injecting means, which will be later fully described. This arrangement serves to superheat the steam and to create high velocity and kinetic energy in the injecting means before contacting with the hydrocarbon oil. I have found in practice that the best results are obtained by raising the temperature of the steam to a high temperature at which substantially all of it will instantly react when brought into the presence of hydrocarbon before contacting with the oil.

The herein disclosed gas making unit for carrying out my process consists of an outer tubular casing having one end closed and having a gas outlet elbow mounted at its other end and a flow-directing plate on top of the elbow. Suspended within the casing from the flow-directing plate are U-shaped superheating tubes and a centrally mounted gas generating chamber. The said unit also comprises an injecting device in which the superheated steam functions to raise

oil from a low level and feed the oil into the said gas generating chamber.

Heat from a furnace is used to produce saturated steam in a constant water level boiler having a steam chamber. From the steam chamber saturated steam under pressure passes through the U-shaped superheating tubes. The said tubes are arranged in series through interconnecting passages in the flow-directing plate. From the U-shaped tubes the superheated steam passes through the injecting device. The superheated steam and the oil are admitted into the heated gas generating chamber as a continuous fog-like mixture by means of the injecting device. The injector nozzle is so constructed that the mixture issuing therefrom will spread in conical form throughout the cylindrical gas generating chamber, the said oil injecting taking place only when and while the temperature in the superheating tubes is high enough to superheat the steam to a temperature at which all of it will react when brought into the presence of hydrocarbon.

An object of this invention is to supply the correct proportion of oil to a definite quantity of the superheated steam.

Another object of this invention is to cause the kinetic energy of the superheated steam to lift the required quantity of hydrocarbon oil from a fixed level below an injector nozzle into a gas generating chamber within an oil gas making unit.

Another object of this invention is to cause a mixed spray of oil and the superheated steam to be introduced into a heated generating chamber and cause reaction between them.

Another object of this invention resides in a self-draining and non-carbonizing injecting device which prevents any oil from remaining and carbonizing in the injecting mechanism when the plant is shut down.

Another object of this invention is to cause the superheated steam and the hydrocarbon oil to meet inside the injector nozzle immediately adjacent to the point of entrance into a reaction zone.

Another object of this invention resides in automatic means for purging the gas generating plant for a definite time before and after gas making.

With the above recited objects and others of a similar nature in view, the preferred form of apparatus for carrying out my process will be shown in the accompanying drawings and pointed out in the claims which form part of this specification.

In the accompanying drawings:

Figure 1 is a vertical central sectional view through the oil gas generating unit.

Figure 2 is a top view of the oil gas generating unit shown in Figure 1.

Figure 3 is a fragmentary sectional view, the section being taken as on line 3-3 in Figure 2.

Figure 4 is a sectional plan view, the section being taken as on line 4-4 in Figure 1.

Figure 5 is an enlarged sectional view of the injector in the position shown in Figure 1.

Figure 6 is an enlarged sectional view of the injector, the section being taken as on line 6-6 in Figure 3.

Figure 7 is a sectional view, taken as on line 7-7 in Figure 5.

Figure 8 is a vertical elevation of the oil gas generating unit under operating conditions in a furnace and connected to a gas scrubber, the furnace being in section as on line 8-8 in Figure 11, and the scrubber being in side elevation.

Figure 9 is a side elevation of the oil gas generator and scrubber.

Figure 10 is a rear elevation of a 3-unit oil gas generator, partly broken away and showing a dutch oven.

Figure 11 is a plan view of a three-unit oil gas generator, including means for automatic control.

Figure 12 is a sectional elevation of a gas generating unit in a furnace and connected to separate superheating units suspended in said furnace.

In the illustrated embodiment of the invention, best shown in Figure 1, reference character 10 indicates an oil gas generating unit comprising a tubular gas generating chamber 11 which is open at its lower end and which is fastened at its upper end to a flow-directing plate 12. The flow-directing plate 12 rests upon the upper end of a gas outlet elbow 13. The elbow 13 is provided with a flange 14 through which pass bolts 15, whereby the elbow is secured to a cover 16 of a furnace 17, best shown in Figure 8.

A tubular casing 23 having a closed lower end and a beveled collar 24 at its upper end is mounted in a beveled seat in the cover 16 in such a manner that it may be removed with facility for repairs. A gasket 25 has been interposed between the elbow 13 and the collar 24 of the casing 23. A gasket 26 has been interposed between the flow-directing plate 12 and the elbow 13. A U-shaped tube 27 has been secured in threaded engagement in the flow-directing plate 12 by means of pipe fittings 28. The U-shaped tube 27 connects at one end to a pipe 29 by means of a passage 30 and a threaded hole 31 in the flow-directing plate 12. The pipe 29 is connected to a saturated steam boiler 32, best shown in Figure 8. The U-shaped tube 27 has been connected at its outlet end 33 with an aperture 34 communicating with an angular passage 35, shown in Figure 2. As best shown in Figure 3, a U-shaped tube 36 similar to the tube 27, has been secured in threaded engagement in the flow-directing plate 12 by means of pipe fittings 37 and connects at one end by means of an aperture 38 with the passage 35. The tube 36 connects at the outlet end with an aperture 39 which communicates with a generally vertical passage 40 in the body 41 of an injector 46. It will thus be seen that the plate 12 comprises an angular passage 35 for reversing the upward flow of steam in the U-shaped tube 27, into a downward flow into the U-shaped tube 36, and

is termed a flow-directing plate. The injector body 41 comprises a lower extension 42 extending into an opening 9 in the flow-directing plate 12 and having a nozzle 43 in threaded engagement. A cover 44 made of high heat resisting material is positioned below the nozzle 43 and seats on top of the gas generating chamber 11 and serves to insulate and protect the nozzle from the intense heat in the gas generating chamber. The high heat resisting material also serves to prevent the heat in gas generating chamber from heating the oil in the injector body to the point of cracking before reaching the gas generating chamber. The cover 44 is provided with an aperture 45 forming an inlet for the gas making elements into the gas generating chamber. The passage 40 terminates at its upper end in an aperture 47 in communication with an annular passage 48 around a perforated member 49, best shown in Figure 5.

The perforated member 49 has radial apertures 50 communicating with an annular passage 51 inside the perforated member. The passage 51 communicates with radial apertures 52 and with a vertical passage 54 in a spindle 53. The passage 54 in its downward direction terminates in an outlet 55 in the nozzle 43. The passage 54 extends upwardly from the apertures 52 to a threaded plug 56 which can be removed for cleaning and blowing out the passage 54, the outlet 55 and the aperture 45 in the cover 44. Steam from the boiler 32 thus passes through the U-shaped tubes 27 and 36 and the injector 46 into the gas generating chamber 11. A threaded gland 57 and packing 58 serve to prevent leakage of steam from the injector body 41. The spindle 53 is in threaded engagement in the body 41 by means of a threaded lower portion 59. It is thus possible to manipulate a handwheel 60 and cause the spindle 53 to move in or out of seating contact in a tapering seat 61 in the nozzle 43 and thus regulate the quantity of oil flowing continuously into the gas generating chamber 11. A hand 62 on the handwheel 60 serves for indicating the adjustment of the spindle 53 in relation to its seat and thus regulating the quantity of oil flowing through the outlet 55.

As best shown in Figure 7, the lower end of the spindle 53 has been formed with a plurality of grooves 63 on its outer periphery and extending from the tapering seat 61, shown in Figure 5, upwards to an inlet passage 64 in the body 41 and communicating with an oil pipe 65. As shown in Figure 1, the oil pipe 65 is connected to the lower end of a sight-feed device 66. An oil pipe 67 is connected at its upper end to a pipe communicating with the upper end of the sight-feed device 66. A predetermined low oil level 68 below the inlet 64 is constantly maintained in the oil pipe 67 by being connected to a float controlled oil level regulator 69, best shown in Figure 8.

The oil level regulator 69 comprises a liquid container 70 in which is a float operated valve 71. The valve 71 serves to control the flow of oil from a storage tank supply pipe 72, thereby maintaining a fixed oil level 68 in the container 70. Oil from the regulator 69 passes through a pipe 73 and through a solenoid controlled oil valve 74 and connects by means of a pipe 75 to the vertical oil pipe 67. When the solenoid controlled oil valve 74 is open, the normal level of the oil in the pipe 67 is the same as that maintained by the float 76 in the oil level regulator 69. The oil in the pipe 67 cannot rise above the normal level 68, until a vacuum is produced in 75

the passage 64 of the injector 48 and in the pipe 67 by the kinetic energy of the steam passing through the outlet 55; and then not until the solenoid valve 74 is opened to permit oil to pass from the oil level regulator 68 to the pipe 67.

As best shown in Figure 8, the vertical furnace 17 is lined with fire-resisting material 18 and is provided at its lower end with a horizontal right-angled extension or dutch oven 19 into which a gas burner 20 throws a flame. A checkered baffle wall 77 constructed of fire bricks 78, spaced apart to form openings 79, is positioned intermediate the dutch oven 19 and the furnace 17. Combustion takes place in the dutch oven where the flame is retained by the baffle wall 77. The hot products of combustion pass through the openings 79 in the baffle wall 77 and upward through the vertical furnace 17 and exit flue 21, thence through an angular flue passage 80, through the boiler 32 to a stack 22. The radiant heat from the furnace bricks 18 acts against the tubular casing 23 and heat transfer takes place, causing the steam passing through the tubes 27 and 36 in the casing 23 to be highly superheated.

The cover 16 of the furnace 17 is mounted on a top angle 81 secured to the furnace. A flame plate 82 has been positioned intermediate the cover 16 and the angle 81, and serves to support heat resisting lining material 83 inside the cover. The boiler 32 is mounted on top of the cover 16 with the angular flue passage 80 in alignment with the flue passage 21 thus making a continuous draft passage from the furnace 17 to the stack 22.

The walls of the angular passage 80 through the boiler 32, provide heating surfaces through which heat transfer takes place from the waste flue gases to the water 84 in the boiler. The water 84 is maintained at a constant level 85 by means of a float-controlled water level regulator 86 best shown in Figure 9. The space above the water level in the boiler forms a saturated steam space 87. A U-shaped water tube 88 may be suspended in the furnace from the boiler into the passage 80 and communicate with the water space at the bottom of the boiler and with the steam space 87 at the top of the boiler and may serve to augment the evaporating capacity of the boiler. A steam outlet pipe 90 leads from the boiler and is connected to a steam header 91, best shown in Figure 11. Saturated steam from the header 91 passes through the pipe 29 to the flow-directing plate 12.

Water is supplied to the boiler 32 from a water pipe 124. The water passes through a pipe 94 to the water level regulator 86 and through a pipe 95 to the water space at the bottom of the boiler. An equalizing pipe 96 attached to the top of the boiler returns to the water level regulator 86. As best shown in Figure 4, the gases generated in the gas generating chamber 11 are forced from the chamber, and pass into an annular space 107 formed by centering arms 108 on the open end portion of the member 11. From the annular space 107 the gases pass upward between the tubular member 11 and the tubular casing 23 into the elbow 13. From the elbow 13, the gases pass through a nipple 97, through a back-pressure or non-return valve 98, through an arch pipe 99 and enter the top of a gas scrubber 100 and are conveyed into a water seal 101 at the bottom of the scrubber by an internal pipe 102. The gases pass upwards from the water seal through a perforated supporting plate 103, through cleaning medium 104, meeting wash

water spray 105 which enters the scrubber through a spray ring 106. The gases leave the scrubber through an outlet pipe 109.

It is to be noted that the embodiment heretofore described relates to a single unit oil gas generator 10, shown in Figures 1 to 9, inclusive. Figures 10 and 11 show a 3-unit oil gas generator 113 built up of three identical units 10 to increase the gas making capacity. It is also to be noted that each unit 10 is an individual oil gas making plant which makes oil gas independently of any of the other units 10, and that one, two or all three of the units 10 may be operated at any time to meet a variable demand for gas. The oil supply pipe 67 for each unit 10 is in communication with an oil supply pipe 75 common to all units 10. The hand wheel 60 on any unit, may be operated to close the spindle 53 on the seat 61 and thus shut off the oil supply and stop gas making in any particular unit, as best shown in Fig. 5.

It is to be noted that the steam passage 54 at the center of the spindle 53, best shown in Figure 5, is of small circumference and there is formed a small and confined heating surface at 25 the center of the spindle. The oil passage 64 is positioned on the outside of the spindle 53 and there is formed a relatively large cooling surface around the outside of the spindle and thus the intense heat in the steam cannot crack the 30 oil and cause carbon deposit during the short period that the oil is in contact with the heated spindle.

The operation of each oil gas generating unit 10 or of any number of the units 10 in the 3-35 unit oil gas generating plant 113 is as follows:

The 3-unit oil gas generating plant 113 comprises a gas storage tank 114 wherein the gas is under pressure. When the pressure in the storage tank drops to a predetermined low point, a bellows 119 contracts and causes a pressure switch 110 mounted thereon to turn on the electric current from the main supply 118. The current opens a solenoid controlled gas supply valve 115 supplying gas to the gas burner 20, and opens 45 the solenoid controlled water supply valve 92 supplying water to the gas scrubber 100. The water level regulator 86 is under constant pressure and is supplied from any suitable source through a pipe 124. From the water level regulator 86, the water is fed and maintained at a regulated level 85 in the boiler 32 (Fig. 9). The electric current also sets a control pyrometer 111 into operation. The gas in the burner 20 is immediately ignited by a gas pilot or by electric 55 ignition (not shown) and the temperature in the furnace 17 commences to rise and the water in the boiler 32 is evaporated into saturated steam by the waste heat in the flue gases passing through the boiler. The saturated steam travels 60 through the superheating tubes 27 and 36 in the tubular casing 23, and finally to the nozzle 43 (Fig. 1). From the nozzle 43, the steam passes into the gas generating chamber 11. When the furnace around the tubular casing 23 reaches 65 a temperature above 1900° F., a thermocouple 120 inserted in the furnace 17 actuates the control pyrometer 111 and turns on an electric current which opens the normally closed solenoid controlled oil valve 74 and admits oil to the pipe 67 70 to a level 68, best shown in Figure 8. The high velocity of the steam passing through the nozzle 43 causes a vacuum in the oil passage 64 (Fig. 5), and causes the oil to rise from the low oil level 68 to a high oil level 112, shown in Figure 75.

1, and to pass through the outlet 55, into the gas generating chamber 11, where reaction takes place and oil gas is generated.

5 The gases pass from the gas generating chamber 11 up through the annular space 107 (Figs. 1 and 4), then through the elbow 13 and enter the gas scrubber 100 through the internal pipe 102 which terminates below the water seal 101. The gases pass upwards from the water seal 101, 10 through the cleaning medium 104 and leave the scrubber through the outlet pipe 109, through the valve 110, the gas pump 117, the bellows 119 and into the storage tank 114.

15 It is to be noted that the control pyrometer 111 not only causes the solenoid controlled oil valve 74 to open but at the same time turns on the electric current which closes the passage in the solenoid operated purging 3-way vent valve 116, which is normally open, venting the plant 20 through a pipe 121 to the atmosphere. Closing the passage through the valve 116 leading to the vent pipe 121, opens a passage through the valve, leading through a pipe 122 to a gas pump 117, thus admitting gas to the pump. The pyrometer 25 also at the same time starts the operation of the pump 117 which takes the gas from the scrubber 100 and delivers same under pressure through the bellows 119 to the gas storage tank 114. The pressure switch 110 is arranged in circuit with a 30 source of current supply through the cable 118.

35 While the gas plant is operating the control pyrometer 111 also controls the temperature in the furnace and around each unit and maintains the temperature as close as possible to a predetermined mean temperature. This is accomplished by means of a solenoid controlled valve 123 which is normally wide open. As the temperature rises to the maximum limit, the control pyrometer turns on an electric current which 40 partly closes the valve 123 to permit only a predetermined minimum supply of gas to pass to the gas burner 20, thereby lowering the temperature in the furnace and in each unit.

45 When the temperature drops to the minimum limit, the pyrometer turns off the electric current which opens the valve 123 to permit a predetermined maximum supply of gas to pass to the gas burner 20, thereby raising the temperature in the furnace and in each unit and controlling the temperature variations within close 50 limits.

55 When the pressure in the gas storage tank 114 reaches a predetermined high pressure, the pressure switch 110 turns off the electric current from the main supply 118 and the electrically operated valves and pyrometer return to their non-operating positions and the generating of oil gas is finished. Then the furnace and each gas making unit and the superheating tubes 60 which were at a temperature above 1900° F. begin to cool off. While the temperature is dropping, the boiler is still generating saturated steam which travels through the respective superheating tubes 27 and 36 and finally to the nozzle 43 (Figure 1). From the nozzle 43, the steam passes into the generating chamber 11, then up through the annular space 107 (Figure 4), then through the elbow 13 (Figure 8), through the valve 98 and pipe 99 and enters the scrubber 100 65 through the pipe 102, and into the water seal 101, where the steam is condensed after having ejected the gas from the entire oil gas generating plant and thereby purging said plant.

70 It is also to be noted that each oil gas generating unit 10 or any number of the units 10,

are also prepurged of entrained air in a like manner before the generating of oil gas begins and while the temperature in the superheating tubes rises to a point above 1900° F., and until gas making starts.

75 As shown in Figure 12, there has been provided a modified arrangement for superheating the steam. The numeral 130 indicates a steam superheating unit comprising a tubular member 131 closed at its lower end 132 and in threaded engagement with a union 133. The tubular member 131 passes through an aperture in the furnace cover 16 and depends from the cover by the union 133 which rests thereon and extends into the furnace 17. A T-shaped member 134 has been threaded into the union 133 and has a packing box 135 through the center of which passes a tube 136 which extends substantially to the bottom of the tubular member 131. A pipe 137 from a steam boiler extends from the 20 T-shaped member 134. Steam entering the pipe 137 passes downward between the outside of the tube 136 and the inside of the tubular member 131 and enters the tube 136 at its lower end and travels upwards and leaves the superheating 25 unit through an elbow 138. The steam in its passage through the superheating unit 130 absorbs heat through the heat exchanging walls of the tubular member 131 in the furnace 17, and becomes superheated.

30 The numeral 139 indicates a unit which is similar in structure to the superheating unit 130. The unit 139 is suspended from the furnace cover 16 and extends into the furnace 17. The elbow 138 of the superheating unit 130 is connected to an elbow 140 on top of the internal tube 141. Superheated steam entering the tube 141 passes downward to the bottom of the tubular member 142 which has a closed lower end 143. The steam passes upward between the 40 outside wall of the internal tube 141 and the inside wall of the tubular member 142, and leaves the unit 139 through a pipe 144. The superheated steam in its passage through the unit 139 absorbs additional heat through the heat exchange- 45 walls of the tubular member 142 in the furnace 17 and becomes highly superheated. The highly superheated steam from the pipe 144 enters the cover member 145 on the oil gas generating unit 146.

50 It will thus be seen that in the oil gas generating unit 146, highly superheated steam enters into the manifold 145 and then directly into the passage 40 of the injector 46. From the passage 40 the steam passes through the aperture 41, 55 through the perforated member 49, into the vertical passage 54, and through the outlet 55 into the gas generating chamber 11. The gas generating chamber 11 depends from the cover member 145 in a manner similar to that shown 60 in Figure 7.

55 It will thus be seen that in the modified oil gas generating unit 146, the superheating of the steam takes place in the separate units 130 and 139 and without the use of the internal U-shaped tubular members 27 and 36, shown in Figures 1 and 4.

65 As shown in Figure 12, the pipe 29 from a steam boiler enters the cover member 145 and connects through a passage 147 with a vertical pipe 148 and with a hollow annular member 149 having a series of spray apertures 150. The member 149 is suitably suspended within the tubular casing 23 near its upper end and surrounds the gas generating chamber 11. Steam from a 70

boiler may thus pass into the spray member 149 and form a steam curtain contacting with the hot metallic outer surface of the chamber 11 and with the hot inner surface of the casing 23 and with the inner surface of the T-piece 13, and prevent the deposit of carbon on the hot metallic surfaces.

I claim:

1. The process of manufacturing oil gas, which 10 consists in first superheating steam separately and while out of contact with hydrocarbon to a temperature at which substantially all of it will react when brought into the presence of hydrocarbon, in continuously conducting said superheated steam directly into a reaction zone, in heating said reaction zone to cause its interior to be at the temperature of said superheated steam, in causing said superheated steam to continuously inject at high velocity a relatively 15 proportioned quantity of unvaporized hydrocarbon oil in an unobstructed path after leaving the injection nozzle into said reaction zone, said oil flowing only concurrently with the flow of said superheated steam, in continuously regulating the

temperature within said reaction zone and maintaining said temperature above 1900° F., said oil gas making reaction taking place substantially completely only while said temperature of said steam and of said reaction zone is maintained above 1900° F.

2. The process of manufacturing oil gas, which 10 consists in first superheating steam separately and while out of contact with hydrocarbon to a temperature at which substantially all of it will react when brought into the presence of hydrocarbon, in continuously conducting said superheated steam directly into a reaction zone, in heating said reaction zone to the temperature of said superheated steam, in causing said superheated steam to continuously transfer a relatively 15 proportioned quantity of unvaporized hydrocarbon oil directly into said reaction zone and the oil flowing only when concurrent with the flow of said superheated steam, in controlling 20 the temperature within said reaction zone above 1900° F. and causing said oil gas making reaction only while said temperature is maintained.

WALTER B. HARRIS.
